DESIGN FOR AN OPHTHALMIC MOUNTING

Edward M. Splaine, Southbridge, Mass., assignor
to American Optical Company, Southbridge,
Mass., a voluntary association of Massachusetts

Application July 18, 1936, Serial No. 63,919

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for an Ophthalmic Mounting, of which the following is a specification, reference being made to the accompanying drawing forming a part thereof.

Fig. I is a front elevation of an ophthalmic mounting showing my new design; and

Fig. II is a plan view of the construction shown in Fig. I.

The characteristic features of my new design are shown in full lines and reside in the provision of relatively slender rim sectors which are curved from a point adjacent the upper temporal sides of the mounting upwardly with a relatively shallow arch which blends into an integral portion of a shorter radius adjacent the nasal sides and which extend downwardly on said sides considerably lower than on the temporal sides. The rim sectors have attached thereto relatively large separate lugs provided with upper surfaces blending into the upper surface of the arch portions with a pleasing sweeping

blend along a line substantially tangent with said rim sectors at the point of attachment of said lugs. The said lugs are fitted and secured to the contour of the rim sectors and taper outwardly towards the nasal sides of the rims and are joined by a relatively thin bridge member resting on the top surface of each of said lugs. The lugs are so formed as to taper from their ends adjacent the bridge connections toward the rim sectors and to blend therewith.

The rim sectors and bridge member are each provided with a shallow sweeping curve when viewed from the top with the bridge of considerably greater width than the width of the rim sectors, the ends of the bridge and attaching lugs blending with each other with the said lugs being tapered toward the rim sectors to produce a pleasing blended effect. The parts are balanced as to their proportions and are provided with contour shapes which blend with each other to produce a pleasing streamline effect.

I claim:

The ornamental design for an ophthalmic mounting substantially as shown and described.

EDWARD M. SPLAINE,
